UNITED STATES PATENT OFFICE.

FRANK L. GRIER, OF MILFORD, DELAWARE, ASSIGNOR TO THE L. D. CAULK CO., OF MILFORD, DELAWARE, A CORPORATION OF DELAWARE.

DESIGN FOR A MORTAR.

50,471.

Specification for Design.

Patented Mar. 20, 1917.

Application filed June 10, 1916. Serial No. 103,042. Term of patent 3½ years.

To all whom it may concern:

Be it known that I, FRANK L. GRIER, a citizen of the United States, residing at Milford, in the county of Sussex and State of Delaware, have invented a new, original, and ornamental Design for a Mortar, of which the following is a specification, reference being had to the accompanying drawings forming part thereof.

Figure 1 is a perspective view of a mortar embodying my new design.

Fig. 2 is a top plan view thereof.

I claim:

The ornamental design for a mortar, as shown.

FRANK L. GRIER.
